TRAVEL GUIDE

Harry E. Banks, Creston, Iowa

Application April 22, 1935, Serial No. 17,674

5 Claims. (Cl. 40—70)

The object of my invention is to provide a travel guide of simple, durable and inexpensive construction adapted to indicate in an attractive form the mileage between certain towns and the route numbers for the automobile roads to be used.

More particularly, it is my object to provide a sign, comprising a fixed member, preferably in disc form, with a second disc rotatably mounted in a proper relation to the first disc. The first disc is provided with the name of the town and with a sight opening or openings. The second disc is provided adjacent its periphery with the names of a number of other towns. Radially inwardly from such names are the indicating characters to show the mileage between the town on the first disc and the respective towns on the second disc. The discs are so arranged that the second disc may be moved to position aligned with the sight opening of the first disc, whereupon the proper mileage and route numbers will appear through the sight opening or openings.

Still another object is to provide a novel means for mounting the discs, one with relation to the other.

With these and other objects in view, my invention consists in the construction, arrangement and combination of the various parts of my travel guide, whereby the objects contemplated are attained, as hereinafter more fully set forth, pointed out in my claims, and illustrated in the accompanying drawing, in which:

Figure 1 is a front elevation of a travel guide embodying my invention.

Figure 2 is an enlarged, front elevation of a part of the travel guide, parts being broken away in order to illustrate the construction of the guide.

Figure 3 is a detailed, sectional view taken on the line 3—3 of Figure 2; and—

Figure 4 is a perspective view of parts of the travel guide, certain portions thereof being broken away.

For advertising purposes, I call my travel guide, the "B-Sure Travel Guide".

It comprises an annular disc-like member 10, preferably made of sheet metal. On the face of the disc 10, there may be provided suitable advertising material as indicated at 11. I preferably also provide in a radial arrangement the name of a town, as at 12. This is preferably used with the word "From" as indicated at 13.

In suitable relation to the name of the town and preferably radially outward therefrom, I provide a sight opening or openings. In the pres-

ent instance, I have shown two radially elongated openings 14 and 15.

I preferably also provide in line with these sight openings a pointer or the like 16.

Suitably rotatably mounted behind the disc 10 is a disc 17 of greater diameter. The mechanical mounting of these discs and their mechanical relation to each other will be later more fully referred to.

The disc 17 has on that part of its face projecting beyond the disc 10 a series of radially arranged names of towns, as indicated at 18.

Radially inwardly from the name of each town, I provide indicating characters 19 to show the official road numbers of the automobile route 15 between the town on the first disc 10 and the aligned town 18 on the second disc 17.

Spaced radially inwardly from the indicating characters 19 are further indicating characters 20 to show the mileage between the town named 20 on the first disc and the particular town on the second disc.

Thus for illustration, there is shown on the disc 17 on the face thereof and outside the disc 10 the name "Corydon" which is the name of a town in Iowa. Radially inwardly from the name "Corydon", there appears on the face of the disc 17 the numerals—34—60—3. These are the official numbers of the roads to be traveled in going from Corydon to Ottumwa, or from Ottumwa to Corydon by the shortest route. These road indicating characters are shown at 19.

Radially inwardly from the characters 19 is the numeral "69" which represents the mileage between Corydon and Ottumwa.

The parts are so arranged that the disc 17 may be rotated to bring any one of the towns shown on the face thereof to position in line with the sight openings 14 and 15. For example, the name "Des Moines" is shown in Figure 2 in line with the sight opening. When the disc 17 is in that position, the appropriate characters 19 and 20 will then be visible through the respective sight openings 15 and 14.

Thus it will be seen in the present instance that when the name "Des Moines" is in line with the sight openings, the numerals "34" and "60" appear through the sight opening 15 and show to the user what roads he can best use in traveling between Des Moines and Ottumwa. The figure "89" appears through the sight opening 14 and shows the mileage between those two towns.

Thus the mileage and the distance between Ottumwa and any of the towns on the disc 17, together with information as to the proper roads

to be taken in traveling between such towns may be readily ascertained by turning the disc 17 until the name of the particular town thereon is in line with the sight openings on the disc 10.

5 It is, of course, important that the two discs be so mounted in relation to each other that the disc 10 will be fixed and the disc 17 rotatable.

It is also important that the disc 17 should be rotated easily and yet that it should remain in 10 any position to which it is adjusted.

For attaining these results, a screw-threaded bolt 21 is extended through the disc 10, which has the hole 22 provided therefor. The disc 17 has a substantially larger central hole 23. Fitted 15 into the hole 23 is a washer 24, which fits in such a way as to permit the free rotation of the disc 17. The washer 24 has an opening 25 and is mounted on the bolt 21. The washer 24 is of greater thickness than the disc 20. Back of the disc 20 20 on the bolt 21 is a washer 26. The bolt 21 may be mounted on a bracket 27 which in turn may be supported on a post or wall 28.

It will be understood that the bolt 21 has a nut 29.

25 It will be observed that when the parts are assembled as shown for instance in Figure 3, the nut may be tightened, and thereupon the disc 10 will be tightly gripped, so that it will not be normally rotatable. On the other hand, 30 owing to the fact that the washer 24 is of greater thickness than the disc 20, the disc 20 may be rotated. In order to prevent accidental rotation of the disc 20 and to hold it in any position to which it may be adjusted and also 35 to keep it from rattling, and further, to prevent rubbing of the discs and consequent obliteration of the characters on the disc 17, I punch projections 30 from the disc 10 near the periphery thereof, and toward the disc 17, thereby providing means for frictionally engaging the disc 17.

It will be seen that there is thus provided a means by which the mileage between one town and a large number of other towns can be readily determined. The guide has enough display 45 features to be attractive to the public. The mechanical structure is simple, durable and efficient.

It is obvious that changes may be made in the details of the construction and arrangement and 50 that the indicating characters may be such as are adapted for any selected series of towns, and it is my purpose to cover by my claims, any modified forms of structure or use of mechanical equivalents, which may be reasonably included 55 within their scope.

The parts may be of any material adaptable for the purpose. The sizes of the sight openings may be varied as may seem advisable and other changes may be made without departing from 60 the spirit of my invention.

I claim as my invention:

1. In a device of the kind described, a front disc, a rear disc of greater diameter, the front disc having a central opening, the second disc 65 having a larger central opening, a washer arranged in the opening of the second disc and being of greater thickness than the second disc, a bolt extended through said openings, and through said washer, a washer on said bolt back of the second disc, a nut on said bolt, whereupon upon tightening of the nut, the first disc will be

gripped between the head of the bolt and the first-named washer and held against rotation, whereas the second disc may be rotated, and parts projecting from the first disc near the periphery thereof for frictionally engaging the 5 second disc.

2. In a device of the kind described, a front disc, a rear disc of greater diameter, the front disc having a central opening, the second disc having a larger central opening, a washer arranged in the opening of the second disc and being of greater thickness than the second disc, a bolt extended through said openings, and through said washer, a washer on said bolt back of the second disc, a nut on said bolt, whereupon 10 upon tightening of the nut, the first disc will be gripped between the head of the bolt and the first-named washer and held against rotation, whereas the second disc may be rotated, said 15 discs having parts near their peripheries in frictional engagement.

3. In a device of the class described, a front disc having characters thereon representing a town and having a sight opening, a second rearward disc arranged concentrically therewith for 25 rotation, and being of larger diameter and having names of towns arranged thereon on the part projecting beyond the first disc, said second disc having arranged thereon, radially inwardly from the names of the respective towns thereon characters representing mileage between the respective towns on the second disc and the town on the first disc, said discs having cooperative means 30 near the periphery of the first disc for frictional engagement.

4. In a travel guide of the kind described, a fixed disc having thereon the name of a town and provided with a sight opening, an adjacent concentric disc behind the first disc mounted for 40 rotation, and being of greater diameter than the first disc, said second disc having names of towns on that portion projecting beyond the first disc and having characters representing distances and characters representing travel routes arranged 45 radially inwardly from the names of the respective towns, so that when the name of a town is radially in line with the sight opening, the appropriate characters representing distances and representing travel routes are visible through the 50 opening.

5. In a travel guide of the kind described, a fixed disc having thereon the name of a town and provided with radially aligned sight openings and having adjacent to the respective openings characters representing mileage and characters 55 representing routes of travel respectively, an adjacent concentric disc behind the first disc mounted for rotation and being of greater diameter than the first disc, said second disc having names of towns on that portion projecting beyond the first disc and having characters representing distances and characters representing travel routes arranged radially inwardly from the names of the respective towns so that when the name of a town on the second disc is radially in line with the sight openings, the appropriate characters representing distances are visible through one of the sight openings and the appropriate characters representing travel routes are visible 60 through the other opening.

HARRY R. BANKS.
